(57) **CLAIM**

The ornamental design for a housing, as shown and described.

DESCRIPTION

This U.S. Design Patent Application is related to U.S. Design patent application Ser. No. 29/752,282 filed Sep. 25, 2020 and entitled "Inspection System", which is incorporated herein by reference in its entirety.

FIG. 1 is a front, left, and top perspective view of the housing embodying the new design;

FIG. 2 is a rear, right, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, right, and top perspective view thereof of the housing mounted to a mobile device (e.g., a mobile robot);

FIG. 10 is a front elevational view thereof; and,

FIG. 11 is a left side elevational view thereof.

The broken lines show portions of a housing which form no part of the claimed design.

The broken lines seen in FIGS. 9, 10, and 11 are for the purpose of showing environmental structure, and form no part of the claimed design.

The "dot-dash" broken lines define the bounds of the claimed design, and form no part thereof.
